UNITED STATES PATENT OFFICE

DAVID POWELL, OF LOS ANGELES, CALIFORNIA

FURRING DEVICE

Application filed May 27, 1929. Serial No. 366,233.

The present invention has relation to means for securing wire lath on the outer wall of frame structures, as a preliminary to applying stucco covering.

5 The studding of frame buildings is usually covered by a layer of boards, called sheathing, and building paper, upon which suitable laths are mounted for the support of stucco surfacing. In the warmer sections of the country, however, where frost is comparatively unknown, it is customary to fasten building paper directly to the studding, and to eliminate the sheathing entirely. On the top of this paper is placed wire lath, which usually is nothing but ordinary poultry wire, and this lath must be fastened to the studding, as no other support is available. It is, furthermore, necessary to mount the lath in spaced relation to the studding, 10 in order to provide a substantial anchorage for the stucco covering.

In view of the foregoing the general object of my invention is to provide an improved furring device. More particularly 15 my object is the provision of a furring device which may be placed with one hand, leaving the other hand free to hold and manipulate a hammer, and which, upon being struck by the hammer, automatically 20 lifts the wire lath away from the studding a predetermined distance. A further object is to hold the lath permanently locked in this position.

To this end my invention consists in the 25 combinations hereinafter fully described and claimed, and illustrated in the accompanying drawing, of which:

Fig. 1 shows the structure of my invention as it appears before it is applied as in practice.

Fig. 2 shows the device inserted under the wire lath it is employed to support,

Fig. 3 shows the position taken by my device, when the lath is clamped in spaced 40 relation to the studding,

Fig. 4 is a perspective view of one of the members of my device, and

Figs. 5 and 6 illustrate a modified form of bracket embodying the invention.

50 The structure of my invention comprises

a spacing bracket 1 and a nail or other suitable driven member 2. The nail is normally held by friction within the bracket, substantially in the relation shown in Fig. 1.

The operator will have within reach, usually 55 in the pocket of his apron, a number of these combination furring brackets. He picks up one and places its toe 3 under a strand 7 of the wire lath, substantially as indicated in Fig. 2. While holding the furring bracket in this position he strikes the nail a light blow, removes his hand and strikes a second, sharp blow. This causes the head of the nail to reach an inclined portion 5 of the bracket and, as the nail continues to travel into the studding, to tip the bracket on its heel 4 until the position shown in Fig. 3 is reached. At this point the nail is arrested by a heel projection 6 of the bracket and the strand of the wire lath is 60 held firmly clamped between the nail and the bracket.

The bracket of my invention is shown made from a flat strip of metal and it is provided with two elongated slots 8 and 9, 65 through which the nail is forced during the process of manufacture of the device. The frictional pressure is sufficient to maintain the nail in this position until struck by the operator's hammer.

The relation of these slots to the shape of the bracket and the length of the slots are important. It is noted that the nail normally is held against the end walls of the slot 8. Pressure of the two fingers holding the bracket, while it is being inserted under the lath wire, tends to maintain the nail in this position. In the clamped position, shown in Fig. 3, it is noticed that the tipping movement has been arrested by the slot end-walls 11 and 12 abutting the nail shank. In this position the bracket is held firmly locked.

It is important to note that the heel projection 6 takes a substantially perpendicular position below the clamped wire, when the nail is driven home, thereby forming a positive stop for the nail head and insuring uniform spacing of the lath on its support.

The importance of the shape of the heel 100

will be appreciated by examining the structure 14 of Figs. 5 and 6. The relation of the heel to the toe remains substantially the same, but the heel has been rounded off considerably more, substantially as indicated by the numeral 16. The incline 5 has been replaced by a substantially semicircular crown 15. The slots of the bracket remain substantially as hereinbefore described.

10 When the operator strikes the nail and its head strikes the crown 15 of the bracket, the impact causes the heel 16 to slip forward and thereby to tip the bracket. The tipping movement is arrested by the end walls of the slots, as above described.

15 This modified bracket may be slightly cheaper to manufacture on account of the larger curves, and it has the advantage of presenting two substantially perpendicular walls resisting the pressure of the nail.

20 I am aware that combination furring brackets have been made and used, but I know of no such devices capable of automatically lifting wire lath to a predetermined height above its support. In other combination furring brackets the use of both hands is required in order to insert the bracket under the lath wire and to raise the lath, compelling the operator to lay down his hammer every time he places a bracket.

25 I claim:

1. A furring device comprising a spacing bracket and a driven member normally held by friction in said bracket, said bracket including, a flat toe for insertion under wire lath, a heel behind said toe upon which the member pivots, and an inclined surface below the head of the driven member along which said head slides when driven in, thereby causing the bracket to swing on its pivot and to raise the wire lath a predetermined distance.

2. The combination with wire lath, of a spacing bracket having alined slots, and a nail normally held seated in said slots by friction, said bracket including, a flat toe for insertion under a strand of said lath, a heel behind said toe upon which the bracket pivots, an inclined surface below the head of said nail along which said head travels when driven in, thereby tipping the bracket on its heel pivot and raising the wire, there being a groove intermediate said toe and said incline in which the wire is held clamped by the head of the nail.

3. The combination with wire lath and a support, of a nail and a bracket perforated normally to hold said nail by friction, said bracket including, a toe insertable under said wire, a heel behind said toe upon which the bracket pivots, an inclined surface in the path of the nail head along which said head slides when the nail is driven into said support, thereby tipping the bracket and spacing the lath from the support, a groove between said

toe and said incline in which the wire is held clamped by the nail, and a wall rising from said heel to the said toe and forming a positive stop for said nail.

4. The combination with a nail and wire lath, of a furring bracket comprising a strip of flat metal bent substantially into the shape of an inverted U, the ends of the strip being curved forward to form a toe insertable under a wire of said lath and a heel behind said toe, there being an elongated perforation in the side of the bracket above said toe, in which said nail normally is held by friction, and an alined perforation in the other bracket side, through which the nail is driven, the head of the driven nail striking the top of the U, thereby tipping the bracket and raising said wire.

5. In combination with a nail and wire lath, an oblong member having on one side a transverse groove the lower side of which forms a toe for insertion under a wire of said lath, the opposite end of the member behind said toe being rounded to form a heel on which the member pivots, the member being lengthwise perforated to receive and frictionally to hold said nail, the head of which, when struck by a hammer, reaches and strikes the opposite end of the member, thereby tipping the member on its heel and raising the wire, which then becomes clamped within said groove by the head of the nail.

In testimony whereof I have hereunto affixed my signature.

DAVID POWELL.
